UNITED STATES PATENT OFFICE.

BERT CLAYPOOL, OF KITTANNING, PENNSYLVANIA.

VEHICLE-TONGUE.

1,084,789.

Specification of Letters Patent.

Patented Jan. 20, 1914.

Application filed December 5, 1912. Serial No. 735,158.

To all whom it may concern:

Be it known that I, BERT CLAYPOOL, a citizen of the United States, residing at Kittanning, in the county of Armstrong and 5 State of Pennsylvania, have invented certain new and useful Improvements in Vehicle-Tongues, of which the following is a specification, reference being had to the accompanying drawings.

10 This invention relates to new and useful improvements in vehicle tongues and more particularly to a tongue which is especially adapted for use upon harvesters and other similar agricultural implements, the object 15 of the invention being to provide a tongue having an arched intermediate portion to allow the horses more freedom in turning corners and sharp curves.

Another object of the invention is to provide 20 a tongue of this character which will possess advantages in points of efficiency and durability, is inexpensive to manufacture and at the same time is simple in construction and operation.

25 With the above and other objects in view, the invention consists in the novel features of construction and the combination and arrangement of parts to be hereinafter more fully described, pointed out in the claim 30 and shown in the accompanying drawings in which—

Figure 1 is a top plan view of a vehicle tongue constructed in accordance with my invention. Fig. 2 is a side elevation, and 35 Fig. 3 is a side elevation illustrating a modified form of the device.

In carrying out my invention, I provide a vehicle tongue which is formed in two sections, namely the inner section 1 and the 40 outer section 2. Arranged between the inner end of the outer section and the outer end of the inner section is an arcuate member 3, said member being constructed of metal, wood or any other suitable material desired. 45 The member 3 is provided at its ends with the spaced ears 4 which are adapted to be arranged upon opposite sides of the end portions of the two sections and rigidly secured thereto by means of the bolts 5.

50 It will be apparent that by constructing the sections 1 and 2 of wood and the arcuate member 3 of metal, that should one of the sections become broken or split in any manner it can be quickly and easily replaced 55 by a new one, said operation being accomplished by the removal of the bolts 5.

It will be apparent from the above that a great advantage is gained by constructing the tongue of sections whereby should one of the sections become broken it can be 60 quickly and readily replaced.

From the above, it will be apparent that the draft animals which are hitched to the whiffletrees 6 will, when turning a corner or sharp curve be disposed beneath the arcuate 65 member 3 instead of being forced against the tongue as is usually the case with the well known form of tongue in use at the present time. It is a well known fact that the more room and freedom a draft animal 70 has, the more pulling power will be gained therefrom and by the use of my improved tongue, it will be apparent that a much heavier load can be drawn than with the straight tongue now in use. 75

It will be apparent that much time is lost and the legs of many draft animals are injured by the low straight tongues sweeping against them when turning corners or sharp curves. 80

In Fig. 3, I have shown a slightly modified form of the invention wherein the intermediate portion of the tongue is formed arcuate in shape as shown at 7 instead of forming the tongue in two sections and connecting the end of each section with a detachable section. In this form of tongue, the arcuate portion will be formed during the construction of the tongue, said tongue being made of iron, wood or any other suitable material. It is to be understood that the main principle involved in my invention is to provide a tongue having an arched intermediate portion which will allow more freedom of the draft animals in turning corners and sharp curves, thus gaining more pulling power from the animal than can be had with the regular straight tongue now in use. 90

From the above description taken in connection with the accompanying drawings, it will be readily apparent that I have provided a simple and durable vehicle tongue which will take the place of the ordinary tongue now in use upon harvesters and other 95 heavy agricultural implements and which will overcome the disadvantage of the horses crowding against the tongue in turning corners and sharp curves and it will also be apparent that the device can be manufactured 100 at an extremely low cost. 105

While I have shown and described the

preferred form of my invention, it will be obvious that various changes in the details of construction and in the proportions may be resorted to for successfully carrying my invention into practice without sacrificing any of the novel features or departing from the scope of the appended claim.

What I claim is:—

10 In a device of the character described, the combination of a vehicle tongue comprising an inner and an outer section, an arcuate member arranged between said sections and having spaced ears formed at each end thereof, the ears of one end of said arcuate

member being disposed upon opposite sides 15 of the outer end of the inner section and the ears upon the other end of the arcuate member being disposed upon opposite sides of the inner end of the outer sections and bolts passing through the ears and the ends of 20 said sections to secure said member to the ends of the sections.

In testimony whereof I hereunto affix my signature in the presence of two witnesses.

BERT CLAYPOOL.
